PRESSURE RELIEF VALVE

Frederick J. Brindisi, Rochester, N.Y., assignor to
Qualitrol Corporation, Fairport, N.Y.

Filed Mar. 16, 1971, Ser. No. 124,999

Term of patent 14 years

Int. Cl. D23—01

U.S. Cl. D23—19

FIG. 1

FIG. 2

FIG. 3

FIG. 4

FIG. 1 is a perspective view of a pressure relief valve embodying my new design showing the front, one end, and one side area thereof;

FIG. 2 is a perspective view showing the back, the opposite end, and the opposite side area thereof;

FIG. 3 is a top plan view of FIG. 1, drawn to a smaller scale; and

FIG. 4 is a section taken on the line 4—4 of FIG. 1, also drawn to a smaller scale.

I claim:

The ornamental design for a pressure relief valve, as shown.
